UNITED STATES PATENT OFFICE.

WILLIAM J. NEWMAN, OF CHICAGO, ILLINOIS.

APPARATUS FOR REMOVING DIRT FROM EXCAVATIONS.

SPECIFICATION forming part of Letters Patent No. 764,202, dated July 5, 1904.

Application filed September 24, 1903. Serial No. 174,427. (No model.)

To all whom it may concern:

Be it known that I, WILLIAM J. NEWMAN, of Chicago, in the county of Cook and State of Illinois, have invented certain new and useful Improvements in Apparatus for Removing Dirt from Excavations; and I do hereby declare that the following is a full, clear, and exact description thereof, reference being had to the accompanying drawings, and to the letters of reference marked thereon, which form a part of this specification.

This invention relates to improvements in apparatus for removing dirt from excavations, such as the cellar-way or basement of a building, preparatory to constructing the building and delivering it to wagons or other vehicles by which it is removed from the premises; and the invention consists in the matters hereinafter set forth, and more particularly pointed out in the appended claims.

A complete apparatus in which my improvements are conveniently embodied embraces, in general terms, an inclined or sloping track extending from the bottom of the excavation to a point outside or on the bank thereof, a dumping car or cars traveling on said track, a structure or frame located outside the excavation upon which the upper or outer end of the track is supported, means on or at said frame for dumping said car, a passage-way beneath said frame into and through which a wagon or other vehicle may pass to receive the dirt dumped from the car, and a plurality of branch tracks laid on the bottom of the excavation and so disposed that cars on said track are accessible for filling from different parts of the excavation, said tracks being so arranged relatively to the foot of the sloping track that the dumping car or cars may be readily transferred from any of said branch tracks to the foot of the inclined track, and a cable operating from a central point located at the foot of the sloping track to draw the cars upwardly from the branch tracks to the sloping track, from whence said car or cars may be drawn up the sloping track to the dumping apparatus outside of the excavation.

The present invention relates more specifically to the arrangement of the parts inside of

the excavation, and such parts may be used with elevating and dumping apparatus of a kind differing from that herein shown.

In the drawings, Figures 1 and 1^a, contained on Sheets 1 and 2, is a view partially in side elevation and partially in section, the section being taken on line 1^a 1^a of Fig. 2 of an apparatus made in accordance with my invention, showing the part thereof located outside the excavation and the part inside the excavation and the inclined track connecting the same. Fig. 2 is a fragmentary top plan view of the parts of the apparatus located within the excavation at or near the foot of the inclined track. Fig. 3 is a fragmentary side elevation of a part of the apparatus located inside the excavation, taken on line 3 3 of Fig. 2. Fig. 4 is a top plan view showing the arrangement of the tracks in the excavation.

As shown in the drawings, A designates the inclined or sloping track, which extends from the bottom of the excavation to the structure or frame on the bank thereof, which supports said upper end of the track A, the dumping apparatus, and a guide-hopper C and is arranged to afford beneath the same a passage-way for a wagon D or other vehicle to receive the dirt dumped from the car through the guide-hopper C and convey it from the premises. B designates a dumping-car which travels on said track A and which is filled with dirt in the excavation and thereafter drawn upwardly therefrom on said track A to the dumping apparatus.

The parts just described are generally like the same parts of the apparatus shown in my prior application for United States Letters Patent, Serial No. 158,594, filed May 25, 1903, with the exception of minor deviations in the structural details of the car and dumping apparatus. The front and rear wheels B' B² of the car travel on the track A, and said car is open at its front and top, the front end thereof being closed by a door B³, which is attached to a swinging frame which is hinged at its rear end to a transverse shaft B⁵, extending transversely across the rear end of the car, as in the car shown in my said prior application. The shaft B⁵ is extended beyond the swinging

70

75

85

95

100

frame B⁴ and is provided at its outer ends with rotative wheels b, which are adapted to strike inclined deflector rails or bars E E, located laterally outside of the track and supported 5 at their lower ends on the sloping track and on their upper ends on said upper frame or structure, as in my prior construction referred to, whereby the car is dumped as it reaches said frame. A difference between the dumping-car herein shown and that of my said prior 10 application is that said wheels b, which engage the deflector or dumping bars E, are journaled on the shaft B⁵ instead of being journaled on the shaft of the rear wheel B², as in the construction of my aforesaid application. The 15 cable F, by which the car is drawn up said sloping track, is attached by chains f to the swinging frame B⁴ and is trained over pulleys F' F² and thence to the drum of a hoisting- 20 engine. (Not shown.) In the present construction the upper bars b' of said swinging door-frame are connected with the door by means of a transverse rod b², which extends 25 removably through forwardly-directed flanges b³ on the door. Said flanges are provided with two or more holes, through either of which 30 said rod may extend, whereby the upper bars may be shifted downwardly at their outer ends with respect to said door. The lower 35 bars b⁴ of said swinging door-frame have slotted connection at their rear ends with the upper bars, as shown in Fig. 1, and are loosely connected at their forward ends with the lower side of the door, thereby permitting such relative movement of the upper bars b' to the door.

The adjustment of the upper bars of the door-frame to the door in the manner described is provided in order to enable the car to be drawn up tracks of different inclinations 40 and at the same time avoid tendency of the draft on the front end of the car lifting the rear end of the car off the track. When the track has a greater slope or inclination than shown in the drawings, the upper bars of said 45 door-frame are moved downwardly into their lower positions. If desired, the wearing-irons e, with which the deflector-bars E are faced, may be turned upwardly at their upper ends, as indicated at e', to constitute stops 50 to prevent the car from being pulled entirely off the deflector-bars when it is being dumped.

The operation of drawing the car up the sloping track and dumping the contents thereof into the hopper C and thence into the vehicle D below is substantially the same as that set forth in my prior application and need not be further described.

Located at the bottom of the excavation are a plurality of tracks, which cover the same in 60 such manner that dirt from all parts of the excavation may be conveniently loaded directly in the car or cars on said tracks, and means are provided whereby by the use of a single cable (preferably operated from the 65 drum of a hoisting-engine outside of the ex-

cavation and worked from a center located at the foot of the sloping track) loaded cars may be transferred from any of said tracks to the sloping track and empty cars from the sloping track to the branch or excavation 70 tracks. I have shown herein one convenient arrangement for effecting this result, though it will be obvious from the foregoing that the details of the arrangement may be varied. The arrangement illustrated will now be described. 75

Located at the bottom of the sloping track A is a track G, extending transversely from one side of the excavation to the other. Said track is located in a depression below the level of the foot of the track A, as clearly shown in Fig. 1^a. Traveling on said track G is a transfer-carriage H, made of open framework construction, as more clearly shown in Figs. 2, 3, and 4, and having flanged wheels 80 h, which travel on the rails of the track G. Supported on the top of said transfer-carriage is a short track consisting of parallel rails h' h', and the level of said track G is such relatively to the level of the foot of the 85 track A that the said track-rails h' are at the level of the track-rails A and when said carriage is standing opposite said track A permit a car to be moved from the transfer-carriage to the track A, and vice versa. Extending in opposite directions from the transfer-track G are a plurality of branch tracks I, laid in the bottom or floor of the excavation, the outer ends of said branch tracks extending 90 to the sides of the excavation and at right 95 angles to said transfer-track, as herein shown, though the directions of the said branch tracks may be varied. The branch tracks I are laid at the same level as the foot of the sloping track, the inner end of which latter is horizontal, so that cars may be transferred from the carriage H to either and all of said branch tracks, and vice versa. The tracks I and horizontal part of the track A will preferably 100 when first laid be set somewhat below the general level of the excavation-floor and will be lowered, as will the track G, as the dirt is removed from the excavation. As herein shown, two of the branch tracks I are located on the same side of the main track G as the track A, 105 while four are located on the other side thereof. 110

The means provided for drawing the car or cars B from the outer ends of the several branch tracks to the transfer-carriage and for thereafter drawing the transfer-carriage loaded with one of the cars B to the foot of the sloping track are made as follows: J designates a cable which is preferably trained over a drum of the same hoisting-engine by which the cars are drawn up the inclined or sloping track and is trained about two sheaves K K, supported on a frame L, located at the foot of the sloping track A. Said cable is provided at its free end with a hook, by which it is connected with the carriage H. The sheaves 115 120 125 130

K K are disposed with their axes of rotation in planes perpendicular to the track G and are rotatively mounted on shafts h , depending from a cross-bar L' of the frame L. Said frame comprises four vertical posts L² L², arranged at the corners of a rectangle, as herein shown, and connected at their upper ends by longitudinal side members L³ L³ and transverse end members L⁴ L⁴. Said beam L' is herein shown as parallel with said side members and is attached at its ends to said end members L⁴. The frame is further strengthened by means of a central transverse member L⁵, parallel with the transverse end members. Arranged opposite to the ends of the branch tracks I, adjacent to the transverse track G, are a plurality of posts M, one for each branch track, and each post is located on the side of the transverse track G remote from its associated branch track. The posts M are surmounted by rotative pulleys or sheaves m. The operation of drawing a loaded car from one of the branch tracks and transferring it to the transverse track G and from thence to the foot of the sloping track is as follows: It will be understood that the cable J remains trained between the sheaves K K at all times and that it travels in contact with one or the other, depending upon toward which end of the track G it is directed. A car after having been dumped in the manner shown in Fig. 1, Sheet 1, and after it has been allowed to travel by gravity down the sloping track to the transfer-carriage at the foot of said track is moved by hand or otherwise, together with the transfer-carriage H, to the inner end of one of the branch tracks I, and thereafter the dumping-car is transferred to that branch track and is moved to the point on such track at which it is to be loaded. After the car has been loaded the free or hooked end of the cable J is carried laterally along the track G toward the branch track on which the loaded car is located and is trained over the pulleys m of that post M which is located in line with the said branch track containing the loaded car and is thence carried to the loaded car and connected with the said car. Preferably the hook j , of said cable is hooked into an eye b⁵ located at the rear end of said dumping-car, as shown in Fig. 4. The hoisting-drum is now started and moves the car inwardly on the branch track and carries it upon the track of the transfer-carriage which has been placed opposite said branch track. Thereafter the cable J is disconnected from the dumping-car and the hook thereof engaged with a hook h² at the rear end of the transfer-carriage. The cable is then released from the sheave m, about which it was trained while the loaded car was being drawn to the transfer-carriage, and its drum is rotated to take up the slack of the cable between the carriage and central sheaves K, and thereafter in the continued rotation of said drum the transfer-carriage is

drawn by said cable to the foot of the inclined or sloping track. The attachment of the cable J to the rear end of the transfer-carriage enables said carriage to be drawn entirely beneath the sheave-frame L and in line with the rails of the track A. After the transfer-carriage has been in this manner brought opposite the lower end of the sloping track A the cable F is connected with the dumping-car, and said dumping-car is thereby drawn up the sloping track to the frame C and the contents thereof dumped in the manner shown in Fig. 1. It will be observed that when the dumping-cars B are drawn inwardly from the branch tracks which extend parallel with the sloping tracks said cars are drawn backwardly and are drawn forwardly from the branches on the other side of the transverse track G toward said transverse track.

With the construction shown it will be observed that as many dumping-cars may be employed as there are branch tracks and that one loaded car may be drawn to the transfer-carriage and from thence transferred to the sloping track, from whence it is carried to the dumping apparatus while the other cars are being filled, and that immediately after one car has been dumped and returned to the excavation another loaded car may be transferred to the sloping track, and in this manner, if a sufficient force be employed to keep said cars filled, the apparatus may be constantly operated to draw the filled cars up the sloping track to the dumping apparatus.

In Fig. 4 I have shown in full lines the cable J arranged to draw a loaded car from one of the branch tracks to the transfer-track and in dotted lines arranged to draw a loaded car from an opposite branch track to the transfer-track, the manner of training the cable J over the sheaves m being thus clearly illustrated.

In lieu of the transfer-track G shown I may employ a central turn-table located at the foot of the sloping track, and in this event the several branch tracks may extend radially from the turn-table instead of being arranged as herein shown.

Other changes in the structural details may be made without departing from the spirit of my invention, and I do not wish to be limited to the details shown except as hereinafter made the subject of specific claims.

I claim as my invention—

1. An apparatus for removing dirt from excavations comprising a sloping track extending from the bottom of the excavation to a point outside the same, a dumping-car travelling on said track, means at the upper end for dumping said car, a plurality of branch tracks laid on the bottom of the excavation, and means for transferring the said car from the branch tracks to the foot of the sloping track and vice versa, embracing a cable which is trained about a centrally-located sheave or

sheaves at the foot of said sloping track and adapted for connection with the car when on any of said branch tracks.

2. An apparatus for removing dirt from excavations comprising a sloping track which extends from the bottom of the excavation to a point outside the same, a dumping-car traveling on said track, means at the upper end of the track for dumping said car, a transfer-track at the foot of the sloping track, branch tracks leading therefrom, a transfer-carriage on said transfer-track adapted to receive or deliver the dumping-car from or to either of the branch tracks and sloping track, and a cable trained about a sheave at the foot of the sloping track and adapted to be connected with the car when on either branch track to transfer it to the carriage, and also to transfer the carriage to the foot of the sloping track.
3. An apparatus for removing dirt from excavations comprising a sloping track which extends from the bottom of the excavation to a point outside the same, a dumping-car traveling on said track, means at the upper end of the track for dumping said car, a transfer-track at the foot of the sloping track, a plurality of branch tracks leading from said transfer-track and means for transferring said dumping-car from the branch tracks to the transfer-track, in position to pass upon the sloping track, comprising a transfer-carriage on said transfer-track, a cable trained about a centrally-located sheave or sheaves at the foot of the sloping track and adapted for connection with said car and carriage, and a sheave located at the end of each branch track on the side of the transfer-track remote from its branch track.
4. An apparatus for removing dirt from excavations comprising a sloping track extending from the bottom of the excavation to a point outside the same, a dumping-car traveling said track, means at the upper end of the track for dumping said car, a transfer-track located at the foot of the sloping track and at a distance below the level of the foot

of said sloping track, a transfer-carriage traveling on said transfer-track and provided with a short track adapted to register with the sloping track, a plurality of branches extending from said transfer-track and located at the level of the foot of the sloping track, a cable trained about a sheave or sheaves at the foot of the sloping track and adapted to be connected with said carriage and with said car, and a sheave located at the inner end of each branch track on the side of the transfer-track remote from said branch track.

5. An apparatus for removing dirt from excavations comprising a sloping track extending from the bottom of the excavation to a point outside the same, a dumping-car traveling on said track, a door for closing the front end of the car, a swinging frame to which the said door is attached and hinged to the rear end of the car, a cable attached to the door at the upper side thereof for drawing the car up said track and means whereby said cable may be attached to the door at different vertically-separated points.

6. An apparatus for removing dirt from excavations comprising a sloping track extending from the bottom of the excavation to a point outside the same, a dumping-car traveling on said track, a door for closing the front end of the car, a swinging frame to which said door is attached comprising two upper side pieces which are hinged at their rear ends to the rear end of the car and are detachably connected at their front ends with the door, a hoisting-cable attached to said side pieces of the frame, and means for raising and lowering the points of attachment of the said side pieces on the door.

In testimony that I claim the foregoing as my invention I affix my signature, in presence of two witnesses, this 21st day of September, A. D. 1903.

WILLIAM J. NEWMAN.
